INVENTOR:

Claudius Dornier.

UNITED STATES PATENT OFFICE.

CLAUDIUS DORNIER, OF FRIEDRICHSHAFEN, GERMANY, ASSIGNOR TO THE FIRM
LUFTSCHIFFBAU ZEPPELIN GESELLSCHAFT MIT BESCHRANKTER HAFTUNG, OF
FRIEDRICHSHAFEN, GERMANY.

CONSTRUCTION MEMBER.

1,419,827.

Specification of Letters Patent. Patented June 13, 1922.

Application filed June 28, 1920. Serial No. 392,558.

To all whom it may concern:

Be it known that I, CLAUDIO DORNIER, a citizen of the German Empire, residing at Friedrichshafen, Germany, have invented 5 certain new and useful Improvements in Construction Members (for which I have made application in Germany, August 31, 1916), of which the following is a specification.

10 My invention refers to construction members and more particularly to a metallic member of especially useful qualities.

It is a well known fact that wherever it is a question of utilizing material to the utmost, endeavours are made to use box beam sections in place of rolled section-girders.

15 My invention refers to a particularly advantageous type of cross-section for weight-bearing constructional parts of high-class 20 material, therefor comparatively small cross-sections.

As can be observed in Fig. 1 of the accompanying drawings two thick plates *a* and *b* are connected by thinner plates *c* provided with flanges in such a manner that a 25 box beam results which encloses a space approximately triangular in section. The section according to Fig. 2 differs from that in Fig. 1 in that the plate *b* is omitted and 30 that in its place the web-plates *d* are deflected at right angles.

This section offers equal moments of inertia for both as; besides that, owing to the wholly closed shape, a considerably greater 35 safety against buckling is vouchsafed than in the usual open box section, without the possibilities of connecting-on being thereby reduced.

The novel member will prove useful whenever 40 small weights must be striven for, thus for instance in portable buildings, such as air-ship sheds and more especially in the construction of air-craft and ships.

In air-craft construction the object of my 45 present invention is mainly suited for cross-beams, longitudinal girders and the like. A particularly advantageous mode of employment is found for this constructional part in the ribs of ships' hulls, floating and other 50 hollow bodies made of steel or light-metal, the shell of these bodies at the same time forming the one boom of the girder.

Figs. 3 and 4 illustrate two modifications of a construction member in accordance with the invention.

Fig. 3 is a section of the supporting plane 55 of a flying-machine from which the application of the invention as a cross-beam may be gathered.

Fig. 4 gives an example from ship-building, 60 the invention being applied to a longitudinal rib.

I claim:

1. A sheet metal girder of triangular section comprising in combination, a pair of 65 converging sheet metal strips fixed to one another along their abutting edges, the free edges being bent outwards so as to extend in line with one another, and a base plate of sheet metal of superior thickness fixed to 70 and connecting said bent edges.

2. A sheet metal girder of triangular section comprising in combination, a pair of converging sheet metal strips, each strip being bent longitudinally so as to present a 75 C-section, a rivet connection between the abutting faces of said strips and a base plate of sheet metal of superior thickness riveted to 80 and connecting the diverging edges of said strips.

3. A sheet metal girder of triangular section comprising in combination, a pair of converging sheet metal strips, a reinforcing strip intermediate and fixed to the converging edges of said strips, the free edges of 85 said strips being bent outwards so as to extend in line with one another and a base plate of sheet metal of superior thickness fixed to and connecting said bent edges.

4. A sheet metal girder of triangular section comprising in combination, a pair of converging sheet metal strips fixed to one another along their abutting edges, the free edges being bent outwards so as to extend in line with one another, and a base plate of 95 sheet metal of superior thickness fixed to and connecting said bent edges, said base plate forming part of the walls of a hollow body.

In testimony whereof I affix my signature. 100

CLAUDIO DORNIER.
